UNITED STATES PATENT OFFICE

WILLIAM H. MUZZY, OF EVANSTON, ILLINOIS, ASSIGNOR TO STEWART-WARNER CORPORATION, OF CHICAGO, ILLINOIS, A CORPORATION OF VIRGINIA

ENGINE-OPERATED FUEL PUMP

Application filed May 3, 1929. Serial No. 360,018.

The purpose of this invention is to provide an improved construction of an engine-operated pump for supplying the carburetor of an internal combustion engine, the improvements of which it consists relating, in one part, to the pump-operating connections, and in another part to the means for clarifying the fuel supply,—relieving it of solid sedimentary material and water,—without liability to embarrassing the operation by the accumulation of the sedimentary solids or water, particularly by the freezing of the accumulated water. It consists in the elements and features of construction shown and described as indicated in the claims.

In the drawings:

Figure 1 is a vertical section of a fuel pumping apparatus containing the invention.

20 Figure 2 is a portion of the same showing the parts at a different position.

Figure 3 is a view similar to Figure 2 showing a third position of the parts.

25 Figure 4 is a different portion of Figure 1 on an enlarged scale.

Figure 5 is a detail plan view of an intermediate lever in the pumping member operating connection.

Referring to the first mentioned part of the invention:—The pump construction shown in the drawings is designed in view of certain defects and embarrassments encountered in the operation of apparatus for like purpose in common use, and to over-30 come and avoid these defects and embarrassments, certain of which arise from the stiffness of the diaphragm desirably employed as a pumping member. It has been found in devices of this character in which a flexible 35 diaphragm is employed under the impulse of a feeding spring and with a positive movement imparted to the diaphragm in the opposite or suction movement by the engine of the car, that at high speeds the diaphragm, 40 though arranged to be actuated positively in one direction by any means, cannot be made to react quickly enough in the opposite direction to follow the cam in the idle phase 45 of the cam cycle; and consequently, after a few cycles at high speed, the diaphragm is

found to be barely moving, and only pulsating the fuel content of the intake passage from the fuel source without lifting the fuel to any sufficient extent for supplying the carburetor, even under the conditions of least 55 fuel requirement.

The main spring for devices of this sort must be fairly flexible and not too strong, or the pressure produced will be much more than desirable for meeting the engine requirements. Such spring is of course limited in respect to the rapidity with which it may force the diaphragm in fuel feeding direction, especially as this fuel feeding movement is resisted by the fuel being fed, which is being forced through comparatively small 60 ports and chambers against a pressure which increases up to the limit for meeting the engine requirements.

For this reason, at high engine speeds the 70 diaphragm in its reaction under the reaction of the main spring lags behind the movement of the positively actuating means driven by the engine, which, in the active phase of the operating cam or other engine part, moves with the speed corresponding to the speed of the engine shaft. This lagging of the diaphragm increases with the speed.

In pumps of this character the pump space above the diaphragm must be very small, 80 because the movement of the diaphragm for producing suction is very slight; and for this reason the pumping member in the present construction a diaphragm, must make a comparatively full stroke in order to act 85 efficiently for suction. While strokes shorter than the full strokes will impel the fuel in the feeding movement, correspondingly short strokes in the opposite direction will not develop suction sufficient to draw gasoline into the pump chamber from the fuel source.

This inefficiency increases with the shortness of the stroke, until the stroke finally only agitates the fuel without lifting the fuel in the intake passage from the fuel source. The full stroke of the diaphragm for suction is therefore desirable, notwithstanding certain advantages of the so-called short stroke.

The object of the present invention is to

produce full stroke of the diaphragm in its movement for intake or suction, regardless of the speed of the operating connections. As this speed at times is as high as fifteen hundred cycles per minute, it will be readily seen that this object cannot be accomplished with the diaphragm making its strokes as frequently as the recurrence of the active phase of the actuating cam or other engine-operated element.

Referring to the drawings:—An actuating cam is shown at 20 on an engine shaft, 21, actuating a lever, 22, positively in the active phase of the cam. Said lever is fulcrumed at 31 in the chamber, 30^a, of the pump casing member, 30, which is arranged to be mounted on the casing (not shown), of the engine to which the shaft, 21, pertains. The lever, 22, at the end opposite that which is engaged by the cam, 20, is connected by a link, 33, with a second lever, 34, pivoted to the upper end of said link intermediate the ends of said second lever, which is connected at the end portion toward the fulcrum, 31, of the first lever with the end of the diaphragm stem, 35. The pump casing member, 30, has a second chamber, 36, partitioned from the chamber, 30^a, by the partition, 37, being formed with a central boss, 38, through which the piston stem, 35, extends, and in which it obtains guidance for the diaphragm strokes.

The chamber, 36, is partitioned by the diaphragm, 40, from the pumping chamber proper, 51, which is formed as a recess in the under side of the casing member, 50, bounded by a flange, 52, which is mated with a flange, 32, which terminates the casing member, 30, and bounds the chamber, 36.

The casing member, 50, has fuel intake passage, 53, in which at 54 there is seen the intake valve, and the discharge passage, 55, in which at 56 there is seen the discharge valve.

The main pump spring, 60, is located in the chamber, 36, encompassing the boss, 38, stopped at its lower end on the partition, 37, and reacting at its upper end on the diaphragm, 40, for giving the latter its feeding stroke.

50 A spring, 70, is provided seated at its lower end in a pocket, 71, formed for that purpose in the bottom plate, 72, of the casing chamber, 30^a, and reacting upwardly on the inner arm, 22^a, of the lever, 22.

55 In the chamber, 30^a, there is suspended on a pivot, 61^a, a fulcrum bar, 61, so named because, as hereinafter described, at certain stages of the operation it affords a fulcrum for the lever, 34, which at another stage is fulcrumed at the opposite end where it is connected to the diaphragm stem.

This fulcrum bar is arranged to depend transversely with respect to the lever, 34, and 60 there is provided a spring, 65, re-acting be-

tween the fulcrum bar near the lower end of the latter and an adjusting screw, 66, set through the casing wall and exteriorly accessible for adjustment to regulate the reaction of the spring on the fulcrum bar for yieldingly holding said bar in the normal position at which it is seen in full line in Figure 1, at which position the left hand end of the lever, 34, rests upon an abrupt or horizontal shoulder, 63, formed by a notch in the right hand edge of the fulcrum bar, the upper edge of the notch being sloped obliquely for a purpose hereinafter described.

Upon considering the construction as thus far described it may be understood that the main spring, 60, operates by its reaction from compression which it receives from the connections with the engine cam, 20, for giving the diaphragm its feeding stroke; and that at the normal position of the parts in the idle phase of the cam with the engine at rest, the diaphragm is at the extreme limit of its fuel feeding stroke, as seen in Figure 1.

And upon further consideration it may be understood that the rotation of the cam to the climax of its active phase causes the lever, 22, to pull the lever, 34, by means of the link, 33, downwardly while said lever, 34, is fulcrumed at the lodgement of its left hand end on the abrupt shoulder, 63, of the notch in the fulcrum bar, 61. And on full consideration it may be understood that upon inability of the main spring, 60, to react quickly enough to thrust the diaphragm fully back to the position seen in Figure 1 during the idle phase of the cam cycle, the reaction of the spring, 70, on the inner arm, 22^a, of the lever, 22, forcing that end of the lever upward, and through the link, 33, forcing upward the lever, 34, at its left hand end, will cause the latter to fulcrum at its pivotal connection with the diaphragm stem, 35, and swing upwardly at its left hand end.

And upon further consideration it may be understood that upon the recurrence of the active phase of the cam cycle, the lever, 34, being now off its fulcrum on the shoulder, 63, of the fulcrum bar, 61, must be pulled down onto that fulcrum before the diaphragm will derive any actuation in the direction of its suction or intake stroke, and will thus derive only so much actuation as will compensate for the reaction which occurred in the brief interval of the idle phase of the cam; thus it will be retracted to the limit of the suction stroke, compressing the spring, 60, to the limit; so that it will always react at its maximum resilient capacity for its fuel feeding stroke whether that stroke be shorter or longer.

In the construction shown, the operation above indicated is somewhat modified by detail features which will now be more particularly described.

The left hand end of the lever, 34, is formed

to present upwardly an inclined or beveled terminal, which, as shown, is made by a right angle fold at the end which was first cut sloping at an angle of about 45°, and the fulcrum bar, 61, formed at the edge toward the left hand bevel of the lever, 34, with the notch bounded as above mentioned at its lower side by the abrupt shoulder, 63, and at the upper side by the sloping shoulder, 64, 5 forms the under side of a cam nose, 67, which overhangs the abrupt shoulder, 63, and projects somewhat beyond that shoulder toward the left hand end of the lever, 34, said nose at its upper side sloping back at an angle 10 adapting the cam nose to be effective for co-operating cam-wise with the end of the lever, 34, in the operation of the structure as will be further described.

At the normal position of the parts seen in Figure 1, being the position which they will assume under the reaction of the several springs when the apparatus is empty and the engine at rest with the cam at the middle point of its idle phase, the left hand end of 20 the lever, 34, is lodged, as stated, on the abrupt horizontal shoulder, 63, of the fulcrum bar, 61, and that shoulder accordingly becomes the fulcrum of the lever, 34, as above described, when the cam rotating through its 25 active phase through the link, 33, causes the lever, 22, to pull downwardly on the lever, 34, and retract the diaphragm against the reaction of the main spring, 60, thus giving the diaphragm its suction stroke as above 30 described.

While the cam is rotating slowly and up to some limit of speed dependent upon the resiliency and stiffness of the spring, 60, and the resistance of the column of fuel in the fuel line from the pump to the carburetor, the 40 spring will react for giving the diaphragm its feeding stroke rapidly enough to keep the lever, 22, following the cam in the idle phase of the cam cycle; and thereby the diaphragm 45 will have its full intake or suction stroke. But when the speed of the cam passes the certain limit indicated, the spring, 60, cannot react rapidly enough to keep the lever, 22, on the cam in the idle phase; and the 50 spring, 70, reacting on the lever, 22, for causing it to follow the cam, and in so doing thrusting the link, 33, against the lever, 34, while the right hand end of the latter connected to the diaphragm stem is still at the 55 low position from which the main spring has not at times retracted, will lift the left hand end of the lever, 34, off the shoulder, 63.

And when this occurs after the cam speed has become so great that the diaphragm is 60 very slightly retracted by the spring, 60, in the idle phase of the cam cycle, the beveled end of the lever, 34, will be swung up past the cam nose, 67, forcing back the fulcrum bar against the reaction of the spring, 65, and 65 snap in above the nose in the recess, 67a, of

the edge of the fulcrum bar, when in the completion of the active phase of the cam cycle, the lever, 34, is pulled down by the link, 33. And the slope of the edge of the fulcrum bar 70 against which the end of the lever, 34, is then resting being too easy to cause it to serve as a fulcrum for the lever, the end of the lever lodged thereon will merely co-operate cam-wise with said slope and swing the fulcrum bar back, while the end of the lever which is thus moved positively by the positive action of the engine cam in its active phase at high speed of rotation, will be swept down past the fulcrum shoulder, 63, and accordingly 75 for lack of a fulcrum for the lever, 34, the diaphragm will derive no actuation from its revolution of the cam, but will continue its feeding stroke under the reaction of the spring, 60, which it was unable to finish in 80 the too short interval between the active phases of the cam cycle.

This sort of operation will be repeated through several revolutions of the cam when the speed is very high until the diaphragm 85 has made its full feeding stroke and is holding the lever, 34, in the position seen in full line in Figure 1 at an idle phase of the cam, so that as the cam moves into its active phase and gives the lever, 34, its positive down pull by means of the link, 33, the lever, 34, is found 90 fulcrumed on the shoulder, 63, so that the actuation which it receives serves to give the diaphragm again a full suction stroke against the reaction of the spring, 60.

Thus it may be understood that the construction results in the diaphragm receiving a full suction stroke as often only as it can react fully therefrom, and being skipped as to actuation for suction in all the revolutions 95 of the cam between those of which it can thus take advantage for deriving a full stroke.

The second part of this invention relates to the construction shown in enlarged view in Figure 2 and will now be described.

The fuel reaches the intake valve, 54, by way of a fuel receiving chamber or fuel and sediment trap formed by a glass bowl, 75, mounted on the under side of an extension, 50a, of the casing member, 50, and held in place detachably by a wire loop, 76, arranged to be tightened by any convenient means, as the customary eccentric, 77, having an operating handle, 55. For rendering the junction between the bowl and the casing suitably tight, a gasket, 79, is interposed, as shown, between the top flange of the bowl and the seat provided for it on the under side of the casing extension, 50a.

The fuel line indicated at 81 from the fuel 125 source or main fuel supply tank, not shown, is connected as seen at 82 for delivering fuel into the fuel and sediment trap chamber, 80, at the top of the latter. The fuel passes out of the chamber, 80, toward the intake 130

valve, 54, by way of a vertical pipe, 83, screwed into the passage, 84, which leads to the valve, 54; and a filtering screen, 85, encompassing the pipe, 83, and having bottom webs obstructing the entrance, 86, of said pipe, serve to exclude sedimentary impurities and water from the pipe and thereby from the pumping chamber.

For the further purpose of excluding from the pipe, 83, and causing to be trapped and retained in the trap chamber any water which may be mixed with the fuel as it comes from the fuel source, there is provided a hood, as shown at 88, made of chamois or like material which is to a large degree impervious to water and not impervious to gasoline, said hood having its bottom web covering the bottom web of the screen and extending from said bottom web up around the screen to a level higher than any expected accumulation of water.

Diaphragm pumps at present are subject to mis-operation in starting after the engine has been standing for some time, as over night in the garage, because the charge in the pump tends to leak back into the main feed pipe past the valves, and allows air to enter the pump chamber and the pipe connecting the pump and the carbureter.

Some of this air passes through the fabric of the diaphragm; some leaks in the pipe joints, and some air and gas leaks back out of the carbureter. The gas in the main feed pipe is of course seeking to return to the main feed tank and this exerts a backward pull on the gas in the bottom chamber and the pipe therefrom to the carbureter and the carbureter fuel chamber.

When the pump is now started at slow speed, it simply alternately expands and compresses the air in the chamber and does not elevate gas from the back tank for some time. It is particularly noticeable when the diaphragm is cold and stiff after the car has been standing in a cold garage over night.

One object of the present invention is to overcome this difficulty and utilize the gasoline that is trapped in the fuel and sediment trap bowl, 80, to form a priming charge that may be readily drawn into the pump chamber by the slow motion of the pump, and start the engine, so that the speed may be increased and the gasoline fed to the pump from the main tank.

This gasoline will be readily drawn into the pump chamber even though the gasoline in the main fuel line from the tank to the pump is not at once lifted, because the air in the top of the trap chamber, 80, will expand to permit the feeding. The gasoline in the trap chamber cannot be drawn back into the main fuel line extending to the tank because there is no siphon action backward out of the bowl. The construction shown and herein-

after described defeats siphon action from the trap chamber.

This result is accomplished by the construction described consisting in the pipe, 83, projecting downwardly into the trap chamber and completely surrounded by the screen, 85, and at the lower part by the chamois hood, 88, as stated, both screen and hood extending over the bottom of the pipe for excluding the entrance of water and dirt from the trap into the pipe.

The withdrawal of fuel from the fuel trap chamber or priming bowl for priming the carbureter which is effected in the operation of the engine by the starter or by the crank, produces a partial vacuum in that chamber, causing fuel to be drawn through the fuel supply line leading from the main tank. And upon consideration of the structure and the operation as indicated, it will be seen that the pipe, 83, will not be emptied at any time in the operation so far as to unseal its lower end port, 86, except for the instant when, by reason of leaky valves and the engine being stopped with the car standing much inclined downwardly, the pipe, 83, might be emptied by siphoning; whereupon the lowering of the liquid in that pipe to the intake port, 86, would cause the siphon to be broken and the air to bubble up through the liquid and occupy the upper part of the trap chamber, causing the liquid to subside in the trap chamber and rise in the pipe, 83, to a balancing point, from which it will be lifted when the engine and pump are started by the starter or by cranking, with the effect above stated of immediately filling the trap chamber the remainder of its depth, except as to a limited space at the upper part, wherein, except for some preventing means, the air which bubbled up through the liquid when the siphon was broken would be trapped.

It is desirable for insuring steady pumping action while the engine is running, that the entire fuel line from the main tank to the pump intake should be filled with liquid; and to insure such condition, notwithstanding the trapping of air in the manner described, there is desirably provided so near the upper end of the pipe, 83, as to be substantially at the top of the cavity of the trap chamber, a small air vent and suction port, 87, through which the engine suction operates for completing the exhaustion of the air from the trap chamber and fuel intake passage after the intake port, 86, is sealed. The size of this port being about that of a No. 72 drill, is not sufficient to prevent the suction of the pump and the engine, when operated by the starter or by the cranking, from withdrawing the liquid contents of the trap chamber for priming the carbureter.

The characteristics of the operation of this structure may be noted as comprising the following:—(a) that the pump is auto-

matically primed or self-priming; (b) that the fuel supply for priming the pump serves also for priming the carburetor; (c) that this priming supply is available, notwithstanding the same trap chamber serves also for accumulating water and sediment separated by means of that chamber from the fuel; (d) that these functions of the trap chamber and connections are not defeated by the freezing of the water which may be accumulated in the bottom of the trap chamber to any depth liable to occur; (e) that the value of the capacity of the trap chamber for these purposes is available, notwithstanding the trapping of air in the upper part of the chamber which results unavoidably from the downward intrusion of the intake pipe in the trap chamber, which is necessary in order that the fuel may be taken from the lower part thereof, this availability being ensured by the restricted suction and air outlet port, 87, at the top of the chamber.

The above recited characteristics of the operation of the structure are obtained by the following above described features:—(1) the provision of the trap chamber from which the fuel is taken from the bottom by way of the entrance port to the pipe, 83, either when the engine is running normally or when it is operated by starter or by cranking; (2) the provision of a limited inlet a short distance above the bottom inlet; (3) the provision of a filter screen enclosing said pipe, 83, including the bottom inlet thereof; (4) the provision by which the air is taken by suction from the top through the vent port, 87.

The trap chamber being of transparent material, makes it serve as an indicator of the condition of the fuel supply, whether failing or choked by the sediment or water.

The importance of providing in some manner for a substantial fuel supply immediately adjacent the pumping apparatus, supplementing the main supply of the relatively distant main tank when the pump is of the diaphragm type, may be understood to be greatly accentuated by the fact that in this type of pump employed with high speed engines the rapidity with which the diaphragm is vibrated necessitates construction providing for a very short stroke; and since the liquid body in the fuel supply line is necessarily moved intermittently by the suction strokes and tends to stand at rest in the interval between suction strokes, its movement must be re-started against its inertia at each suction stroke; and the stroke being, as above noticed, very short, affords too little time for overcoming the inertia of the long liquid body extending back to the main tank. The provision of the near-by supply content in the trap chamber is designed to meet this difficulty.

It should accordingly be understood that

the invention is not limited to the specific details of construction described, although certain of these details are claimed as constituting preferable means for serving the purpose stated, but the details may be modified and departed from in many respects without departure from the invention as directed to the purpose indicated.

I claim:

1. An apparatus for supplying fuel to the carburetor of an internal combustion engine comprising a casing having a pumping chamber with a flexible diaphragm constituting the pumping member and a main spring reacting on the diaphragm for giving it its fuel impelling movement; engine-operated connections for giving the diaphragm its fuel intake movement, comprising a one-way active cam, a main lever fulcrumed in the casing having an arm exposed to actuation by the cam in the active phase of the cam cycle; a second spring reacting on the lever for causing it to follow the cam in the idle phase of the cam cycle; operating connections from said lever to the diaphragm comprising an intermediate lever and a part arranged to serve as a fulcrum for said intermediate lever in the movement of the lever in the direction for giving the diaphragm its fuel intake movement and to permit the lever to leave said fulcrum when actuated in the reverse direction by said second spring.

2. In the construction defined in claim 1, the engine-operated connections including a diaphragm stem to which the intermediate lever is connected at the end of said intermediate lever opposite that at which it is permitted to leave the fulcrum, and a link connecting the main lever to the intermediate lever at a point in the latter intermediate its said end.

3. An apparatus for supplying fuel to the carburetor of an internal combustion engine comprising a casing having a pumping chamber with a flexible diaphragm constituting the pumping member; a main spring reacting on the diaphragm in the direction for giving it its fuel impelling movement; a lever operatively connected with the diaphragm; a fulcrum element in the casing having an abutment on which said lever is arranged to lodge for fulcruming at its said lodgement in the movement of the lever in the fuel intake movement of the diaphragm, with freedom of the lever to leave said fulcrum in the reverse movement of the diaphragm, and engine operated connections arranged to actuate said lever positively in the direction for holding it lodged on said fulcrum and spring means for actuating said lever in a direction for leaving its said fulcrum.

4. An apparatus for supplying fuel to the carburetor of an internal combustion engine comprising a casing having a pumping

chamber with a flexible diaphragm constituting the pumping member, and a main spring reacting on the diaphragm for giving it its fuel impelling movement; engine-operated connections for giving the diaphragm its full intake movement comprising an actuator having alternate active and idle phases in its cycle, said connections being arranged to give the diaphragm said 5 intake movement positively in the active phase of the actuator cycle, and spring means for causing the actuated part to follow said actuator in its idle phase, said connections comprising a lever operatively connected 10 with the diaphragm, and a fulcrum for said lever, said parts being arranged to permit the lever to leave said fulcrum in the movement for following the idle phase of the actuator and for avoiding said fulcrum in its 15 return in the succeeding active phase; whereby the diaphragm derives a succeeding positive actuation for its fuel intake movement only after it has had time to complete a fuel impelling movement under the reaction of the 20 main spring from a preceding positive actuation.

5. The construction defined in claim 3, the fulcrum element being a bar mounted movably in the casing, a spring reacting on said 25 bar for holding it in position for affording fulcrum to the lever, the lever and said bar being co-operatively formed for adapting the lever to displace the bar in the movement of the lever for leaving its said fulcrum 30 lodgement.

6. In the construction defined in claim 3, the fulcrum member being movably mounted and yieldingly held positioned for the lodgement of the lever on the fulcrum abutment, 35 and having a cam projection spaced from the abutment in the direction from the latter in which the lever moves in leaving said fulcrum abutment, said fulcrum member being arranged to co-operate with the lever in said 40 movement of the latter for moving the fulcrum member to carry the fulcrum out of the path of the lever's return movement; whereby said return movement when exceeding some predetermined speed carries the lever 45 beyond the abutment for defeating the fulcrumming of the lever.

In testimony whereof, I have hereunto set my hand at Chicago, Illinois, this 26th day of April, 1929.

WILLIAM H. MUZZY.
